UNITED STATES PATENT OFFICE

131,657

DESIGN FOR A PORTABLE ELECTRIC SCREW DRIVER UNIT

Alonzo G. Decker, Baltimore County, Md., assignor to The Black and Decker Manufacturing Company, a corporation of Maryland

Application July 17, 1941, Serial No. 102,197

Term of patent 7 years

To all whom it may concern:

Be it known that I, Alonzo G. Decker, a citizen of the United States and a resident of Baltimore County, State of Maryland, have invented a new, original, and ornamental Design for a Portable Electric Screw Driver Unit, of which the following is a specification, reference being had to the accompanying drawing, forming part thereof.

In the drawing:

Fig. 1 is a side elevational view of my portable electric screw driver unit,

Fig. 2 is a front elevational view of the same, and

Fig. 3 is a top plan view thereof.

I claim:

The ornamental design for a portable electric screw driver unit substantially as shown.

ALONZO G. DECKER.
